LORNE H. COLPE, OF SAN FRANCISCO, CALIFORNIA

MOUTHPIECE FOR CIGARETTES

Application filed November 16, 1929. Serial No. 407,840.

The invention forming the subject matter of this application relates to mouthpieces, and more particularly to a mouthpiece adapted for attachment to the end of a cigarette.

An object of the invention is to provide a mouthpiece for cigarettes which when attached to one end of the cigarette will prevent particles of tobacco from entering the mouth of the smoker and wherein the said mouthpiece is arranged on the end of the cigarette in such a manner as to hold the said end in a relatively flattened tapered position.

Another object of the invention is to provide a cigarette mouthpiece of the character described, which can be readily made of paper or sheet cork stampings, and which at the same time is light and strong.

Another object of the invention is to provide a cigarette mouthpiece which is highly useful and simple in construction. Convenience of arrangement, lightness and comparative inexpensive of manufacture are further objects which have been borne in mind in the production and development of the invention.

With the foregoing and other objects in view, which will be made manifest in the following detailed description and specifically pointed out in the appended claims, reference is had to the accompanying drawing for the illustrative embodiment of the invention, wherein:

Fig. 1 is a side view of the mouthpiece shown attached to a cigarette and wherein the mouthpiece and a portion of the cigarette are shown in section;

Fig. 2 is a top plan view of the mouthpiece as attached to the end of a cigarette;

Fig. 3 is an end view of the mouthpiece and cigarette shown on an enlarged scale.

Fig. 4 is a plan view of the cigarette mouthpiece prior to its attachment to a cigarette.

Fig. 5 is a longitudinal sectional view taken on the line 5-5 of Fig. 4.

Referring to the accompanying drawing wherein similar reference characters designate similar parts throughout, the various figures described above adequately illustrate

my invention, and the following detailed description is commensurate with the above mentioned drawing in enabling an artisan to construct and assemble the constituent parts of the same.

In carrying out my invention, I make use of a cigarette mouthpiece designated as an entirely by the reference numeral 5. In its preferred form the mouthpiece 5 consists of a thin flat strip of material 6 such as paper, sheet cork, or any other material which may be adapted for the purpose. As shown in Fig. 4, the mouthpiece strip 6 is elliptical in form, and is provided with a plurality of relatively small equally spaced apart openings 7 which extend transversely across the center of said strip.

In order to prepare the strip 6 for attachment to the end of a cigarette indicated by the numeral 11, the said strip is adapted to be folded along the dotted lines 8 shown on each side of the openings 7 in Fig. 4. When the strip 6 is folded in this manner it will consist of a substantially rectangular center portion 9 having two similar flaps 10 extending from the opposite longitudinal edges of said center portion as is clearly shown in Figs. 1 and 2. For the purpose of securing the mouthpiece 5 to the end of a cigarette indicated by the numeral 11, it is preferable that the inside surfaces of both of the flaps 10 be coated with an adhesive substance which when moistened will adhere to paper covering 12 of the cigarette 11.

It will be noted that the width of the center portion 9 of the mouthpiece 5 is substantially smaller than the diameter of the cigarette 11, therefore in attaching the mouthpiece 5 to the end of said cigarette it will first be necessary to flatten the cigarette end to conform to the width of said center portion. When the end of the cigarette 11 has been flattened sufficiently, the mouthpiece 5 is fitted over said end so that the flaps 10 overlie the body of the cigarette at diametrically opposite points thereon, as shown in Fig. 1. The adhesive substance on the inside surfaces of said flaps 10 is then moistened and the flaps are pressed against the body of the cigarette so as to adhere to

the paper covering 12 thereof. It will now be seen that the mouthpiece 5 provides a flattened tapered end to the cigarette which is extremely comfortable in the mouth of the smoker. The end portion 9 of the mouthpiece 5 prevents particles of tobacco from entering the smoker's mouth, while the openings 7 in said end allow the smoke to pass unimpeded through said end. It is important of course 10 that said openings be of such small size as to prevent any tobacco from passing therethrough.

From the foregoing, it is thought that the construction, use and many advantages of the 15 herein described cigarette mouthpiece will be readily understood without further description, and it will also be understood that changes in the form, proportion, and minor details of construction may be resorted to 20 without departing from the spirit of the invention or sacrificing any of the advantages thereof.

What I claim is:—

1. A mouthpiece for cigarettes comprising 25 a substantially rectangular end portion of less width than the diameter of a cigarette and having a plurality of openings therein through which smoke may pass, and an integral flap extending from each of the 30 opposite longitudinal sides of said end portion so as to overlie one end of a cigarette.

2. A mouthpiece for cigarettes comprising a thin strip of flexible material elliptical in form, and folded transversely so as to form 35 a substantially rectangular central end portion having flaps extending from the opposite longitudinal edges thereof, which flaps are adapted to overlie one end of a cigarette, said substantially rectangular end portion 40 being of less width than the diameter of a cigarette and having a plurality of openings therein through which smoke may pass.

In testimony whereof I have affixed my signature.

45 LORNE H. COLPE.
